UNITED STATES PATENT OFFICE

ALBERT K. SMITH, OF WEST ORANGE, NEW JERSEY, ASSIGNOR TO THE HILLS BROTHERS COMPANY, INC., A CORPORATION OF NEW YORK

ROASTING MACHINE

Application filed July 9, 1927. Serial No. 204,470.

This invention relates to fruit holders for supporting a fruit, such as a pimento pepper, as it is carried through a roasting or singeing oven to remove the skin therefrom.

It is the purpose of this invention to provide a holder for supporting a pimento while conducting it through a roasting oven, where the temperature is relatively very high, which will firmly grip the pimento and yet readily release it at the exit end of the roasting chamber and which will function properly under continuous use at the high temperature employed.

It is also an object of my invention to construct a suitable holder which readily may be adapted and be used with chain conveyors in continuous operating machines.

I accomplish these objects by providing a head upon which a pimento which has previously been cored may be supported in inverted position, the head having associated therewith a pair of pivoted fingers which project therethrough and in one position grip the inner surface of the pimento at spaced points and also having a depending flange which may be pivotally attached to a chain conveyor.

A detailed description will be given in connection with the drawings in which:

Fig. 1 is a side elevation of two of the supporting heads mounted upon a conveyor, some of the elements having been omitted for clearness;

Fig. 2 is a section on line 2—2 of Fig. 1;

Fig. 3 is a plan of a single head.

In the embodiment shown in the drawings by way of illustration I provide a head having a somewhat rectangular top portion 1 which has a circular boss 2 extending from the upper face thereof having a diameter approximately the same as the opening cut into a pimento by the coring operation and over which a pimento may be placed. Adjacent to this boss and arranged around the outer periphery thereof are a plurality of projections 3 somewhat lower in height which ex-

tend only slightly above the upper surface of the top portion 1 and serve as rests or stops upon which the edge of the pimento rests when placed in inverted position upon the boss 2.

The upper portion is formed with an elongated centrally disposed vertical slot 4 extending therethrough from top to bottom. Integrally with the portion 1 and extending downwardly therefrom is a relatively thin bifurcated depending flange or web 5 which is arcuate upon its lower edge and which extends laterally beyond each side of the rectangular portion 1 for a substantial distance in a direction perpendicular to the length of the slot 4. Immediately below the upper section 1 the web 5 is cut away to provide an opening therethrough for purposes to be later described.

Disposed within the elongated slot 4 are a pair of gripping fingers each of which comprises a flat barlike member 6 having an upper curved end 7 and a lower enlarged end or foot 8. These fingers are formed with a lug portion 9 projecting laterally from one edge thereof which is bored to receive a pivot pin 10 very loosely, to pivotally secure the fingers 6 to the upper portion 1 at a point which is removed from the center of gravity of the fingers in such a manner that the fingers normally fall with the upper curved ends 7 in abutting relationship when assembled in the head. These fingers are supported within the slot 4 with the upper curved ends 7 facing outwardly and the lower foot portions 8 projecting through the cut-away portion in the flange 5.

A U-shaped cam member 11 is positioned below the head in such a manner that the two side arms 12 and 13 thereof extend upwardly and constitute cam tracks which lie adjacent the lower ends 8 of the fingers 6. The distance between the tracks 12 and 13 may be varied so as to control the relative positions of the fingers 6 and swing them upon their

6 pivots 10 to move the upper ends 7 toward or from each other to grip or release a pimento placed upon the boss 2 and over the curved ends 7. The cam element 11 is supported upon a tubular support 14 which may be connected to the source of cold water (not shown) for cooling purposes.

10 For utilization in connection with a conveyor system the bifurcated web 5 is loosely pivoted by a single pin 15 to a connecting link 16 which is attached to a conveyor chain 17, the connecting link 16 being pivotally connected to a chain at a plurality of points as, for example, by pins 18 and 19. In order to prevent direct wear upon the cam a wear 15 plate 20 is placed between the conveyor chain and the cam. It is to be noted that all the pivot pins are considerably smaller than the aperture through which they extend in order to permit free movement thereof at high 20 temperatures when the metal is expanded. Also that the length of the web 5 in the direction of motion is such as to rigidly support the head and prevent it from turning 25 upon a vertical axis whereas the arcuate edge will permit of short bends as the chain traverses the sprockets at the ends thereof.

30 In operation the supporting heads as previously described are customarily used in multiple upon a conveyor chain or other conveying device and the whole head and chain is caused to traverse a roasting tunnel (not shown). As the heads approach the tunnel a pimento may be placed in inverted position 35 over the boss 2 while the curved ends 7 of the fingers 6 are in close abutting relationship after which the cam tracks 12 and 13 will converge and separate the curved ends 7 by contacting with the feet 8 and swinging the fingers 6 upon their pivots 10 whereby the pimento is firmly gripped and held in upright inverted position upon the boss 2 by the fingers 6 which frictionally grip the inner surface of the pimento and at points within the 40 pimento where the diameter is greater than the opening cut into the pimento. As the head emerges from the tunnel the cam tracks again diverge and permit the fingers to swing upon their pivots by the action of gravity and 45 move the curved ends 6 toward each other and allow the pimento to fall from the support. It is obvious that various changes in the details of construction may be made without departing from the spirit and scope of the 50 invention as defined in the appended claims.

I claim:

1. A fruit holder for use in roasting machines comprising a head provided with a support for a previously cored fruit and a 60 portion extending above the support to enter the fruit, and a pair of pivoted fingers extending above said portion adapted to extend into the fruit on said support and engage the inner surfaces thereof to frictionally hold the fruit on said support.

2. A fruit holder for use in roasting machines comprising a head adapted to support a previously cored fruit thereover, a pair of fingers pivoted in the head intermediate their ends, the upper ends of which extend above said head and into the fruit supported thereby, the lower ends of said fingers projecting out of said head and means for engaging the lower ends of said fingers and moving them relatively to each other to cause the fingers to engage the inner surface of the fruit to frictionally hold the fruit upon said head. 70

3. A fruit holder for use in roasting machines comprising a head adapted to support a previously cored fruit thereover, a pair of fingers pivoted intermediate their ends, the upper ends of which project above said head and into said fruit, a pair of cam tracks adapted to contact with the lower ends of said fingers to move them relatively to each other to cause the upper ends to engage the inner surface of said fruit to frictionally hold the fruit upon said head. 75

4. A fruit holder for use in roasting machines comprising a head adapted to support a previously cored fruit thereover, a pair of fingers pivoted intermediate their ends at a point removed from their center of gravity, the upper ends of which project above said head and into said fruit, a pair of cam tracks adapted to contact with the lower ends of said fingers to move them relatively to each other to cause the upper ends to engage the inner surface of said fruit to hold the same upon the holder. 90

5. A fruit holder for use in roasting machines comprising a head adapted to support a previously cored fruit thereover having a flange depending therefrom for attachment to a conveyor, a pair of pivoted fingers extending above said head and adapted to extend into the fruit on said head and engage the inner surface thereof to frictionally hold the fruit on said head. 95

6. A fruit holder for use in roasting machines comprising a head adapted to support a previously cored fruit thereover having a flange depending therefrom for attachment to a conveyor, a pair of pivoted fingers extending above said head and adapted to extend into the fruit on said head and engage the inner surface thereof to frictionally hold the fruit on said head, and means for pivotally securing said flange to said conveyor. 100

7. A fruit holder for use in roasting machines comprising a head having a raised boss thereon adapted to enter a previously cored fruit and a support below the boss for supporting the fruit at the edges of the opening in the fruit, a pair of pivoted fingers extending above said boss and adapted to extend into the fruit on said head and engage the inner surface thereof to frictionally hold the fruit on said head. 105

8. A fruit holder for use in roasting machines comprising a head having a raised boss thereon adapted to support a previously cored fruit thereover having a flange depending therefrom for attachment to a conveyor, 5 a pair of pivoted fingers extending above said head and adapted to extend into the fruit on said head and engage the inner surface thereof to frictionally hold the fruit on said head.

10 9. A fruit holder for use in roasting machines comprising a head adapted to support a previously cored fruit thereover, a pair of fingers pivoted intermediate their ends, the 15 upper ends of which project above said head and into said fruit, a U-shaped cam adapted to contact with the lower ends of said fingers to move them relatively to each other to cause the upper ends to engage the inner surface of said fruit.

20 10. The combination with a chain conveyor of a fruit holder for use in a roasting machine comprising a head adapted to support a previously cored fruit thereover having a plurality of pivoted fingers therein extending 25 above said head for gripping the interior surfaces of said fruit, a flange extending therefrom, and a link pivotally connected to said flange and to said chain conveyor.

30 11. The combination with a conveyor of a fruit holder for use in a roasting machine comprising a head adapted to support a previously cored fruit thereover, said head having a plurality of fingers pivoted thereto and extending 35 above said head for gripping the interior surfaces of said fruit, a flange depending therefrom and a link pivotally connecting said flange to said conveyor.

40 12. The combination with a chain conveyor of a fruit holder for use in a roasting machine comprising a head adapted to support a previously cored fruit thereover having a plurality of pivoted fingers therein extending above said head for gripping the interior surfaces of said fruit, a flange extending therefrom, and a link pivotally connected to said flange at a single point and to said conveyor 45 at a plurality of points.

50 13. A fruit holder for use in roasting machines, comprising a head adapted to support a previously cored fruit thereover, including a plurality of pivoted fingers extending above said head and having projecting ends adapted to engage the inner surface of fruit 55 supported on the head, and means acting on the other ends for causing their projecting ends to move apart to engage said fruit.

60 14. A fruit holder for use in roasting machines which comprises a head provided with a support for previously cored fruit and having a projecting portion entering a piece of fruit on the support, and means extending through the free end of said portion and movable to engage the inner surface of a piece of 65 fruit on the support.

15. A fruit holder for use in roasting machines which comprises a head provided with a support for previously cored fruit and having a projecting portion entering a piece of fruit on the support for centering the fruit, 70 and a pair of elements in the head extending through the free end of said portion and movable apart to engage the inner surface of the fruit on the support at spaced points.

In witness whereof, I hereunto subscribe 75 my signature.
